FREDERICK BERNARD DÖRING, OF LONDON, ENGLAND.

Letters Patent No. 77,597, dated May 5, 1868; patented in England, January 7, 1867.

IMPROVED ROCK-DRILLING MACHINE.

The Schedule referred to in these Letters Patent and making part of the same.

TO ALL WHOM IT MAY CONCERN:

Be it known that I, FREDERICK BERNARD DÖRING, have invented or discovered Improvements in Engines for Boring and Working Rock and other material; and I do hereby declare that the following is a full, true, and exact description thereof, reference being had to the accompanying drawings, and to the letters and figures marked thereon; that is to say—

My invention mainly consists in the employment, in combination with the ordinary cylinder, in which the piston which actuates the boring-tool works, of a small distributing-cylinder, formed with ports, as hereafter described; also in the employment, in combination with this small distributing-cylinder, of a valve-cylinder and two other cylinders, the piston-rods of which are connected to pawls, as hereafter mentioned. These three cylinders are in communication with the small distributing-cylinder, which thus works the valve of the ordinary cylinder, and the pawls, which act upon ratchet-wheels for producing the rotary motion of the piston and tool, and the advance motion of the engine. The small cylinder is placed at the side of the ordinary cylinder, or in other convenient position, and is supplied with compressed air, or other motive-agent, from the main pipe. The small distributing-cylinder has two pistons, between which the air is always contained. In the back stroke of these two pistons, the air issues through an outlet-port or ports, in communication, by pipes, with the valve-cylinder above referred to, which works the slide-valve of the ordinary cylinder, and with the two other cylinders above referred to, the piston of one of which works the pawl, which, by means of a ratchet-wheel, imparts rotary motion to the ordinary piston and tool, while the piston of the other of these two cylinders works the pawl, by means of which the advance movement is given to the engine as the work proceeds. When the cylinder of the advance movement is vertical or inclined, I sometimes fit a spring on the piston or piston-rod, to prevent this piston and the pawl falling, except when the tool has cut to the required depth, but the spring of the pawl will generally be found sufficient for the purpose.

In the forward stroke of the pistons of the small cylinder, the air issues through an outlet-port or ports in communication with the valve-cylinder, and with the cylinder connected with the pawl of the rotary movement; and when the tool has cut to a sufficient depth, the pistons of the small distributing-cylinder are enabled to make a forward stroke of sufficient length to open another outlet-port, in communication with the cylinder connected with the pawl of the advance movement, whereby the spring of this pawl (when a spring is used) is overcome, and the pawl brought back and made to catch into another tooth of its ratchet-wheel, which is then caused to rotate the distance of one tooth, when the main piston makes its back stroke, and thus advance the engine.

The piston-rod of the small cylinder or cylinders is or are connected by a cross-head in front, or at the back of the piston-rod of the ordinary cylinder, from which the movements of the distributing-pistons are obtained.

Figure 1 of the accompanying drawings is a plan of the upper side,

Figure 2 is a view from below,

Figure 3 a front; and

Figure 4 a back-end view of a boring-engine, constructed as hereinbefore described.

Figure 5 is a longitudinal section, and

Figure 6 a similar section, at right angles thereto.

A is the ordinary cylinder, carried between two longitudinal bars, B C, one of which, B, is threaded. F is the piston, and G the piston-rod, the front end of which carries the borer or tool. The piston-rod and piston have a square longitudinal aperture, in which a square rod, H, fits. The rear end of this rod is carried through the back of the cylinder, and carries a ratchet-wheel, I. When this wheel is caused to rotate, the central rod H turns, together with the piston, piston-rod, and tool. The piston, however, is free to move backward and forward independently of the rod H. K K are the inlet-ports of the cylinder A, and L is the port through which the air is received. M is my small distributing-cylinder, shown separately in section in Figure 7. N is the valve-cylinder, O the cylinder in connection with the ratchet-wheel I, and P is the cylinder in connection

with the ratchet-wheel D. These three cylinders are, as before stated, in communication with the distributing-cylinder M. This cylinder is placed at the side, or forms part of the ordinary cylinder A, as shown, or in other convenient position, and is supplied with compressed air or other motive-agent through the port or aperture Q, (see fig. 7,) which is in connection with the main pipe L. The cylinder M has two pistons, R R, on one rod, S, between which piston the air is always contained. The front end of the rod is connected by a cross-head or collar, T, to the main piston-rod, G, so that the two rods move simultaneously and equally. In the back stroke of the two pistons, R R, the air issues through an outlet-port, U, in communication, by pipes V V V, with the valve-cylinder N, and with the other two cylinders, O and P. The air is thus admitted into the valve-cylinder N, and the valve moved back, so as to admit air into the ordinary cylinder A, to produce the forward stroke of the piston F, and consequently of the pistons R R, while at the same time the air admitted into the cylinder O drives forward the piston of this cylinder. This piston causes the pawl X to move the ratchet-wheel I the distance of one tooth, and thus produce the partial rotary-motion of the piston F and tool. The air at the same time is admitted into the cylinder P, and, if the piston of this cylinder is at the back end of the cylinder, it drives the piston, and causes the pawl Z to move the ratchet-wheel D the distance of one tooth, and thereby advance the engine.

In the forward stroke of the pistons F and R, the air issues through an outlet-port, a, in communication, by pipes b, with the valve-cylinder N, and with the cylinder O of the rotary movement, whereby the valve is moved over to supply air at the front end of the cylinder A, and the pawl X is drawn back into another tooth of the wheel I, ready to act at the next forward stroke of its piston. The outlet-port a is not in communication with the cylinder P of the advance movement, and the piston of this cylinder, therefore, remains at the forward end, and the wheel D is not acted on by its pawl at the next back stroke of the pistons F and R; but when the tool has cut to a certain determined depth, the pistons R are enabled to make a forward stroke sufficient to open an outlet-port, c, as well as the port a, and the air then passes through the port c, and a pipe, d, into the forward end of the cylinder P, whereby the piston of this cylinder makes its back stroke, drawing the pawl z into the next tooth of the wheel D, ready to move this wheel forward at the next back stroke of the pistons R. When the air from the port U enters the back end of the cylinder P, drives the piston of the cylinder P, and actuates the pawl Z so as to produce the advance movement. g is an outlet in the cylinder M, to form an exhaust from the pipes V V V, and f is another outlet, to form an exhaust from the pipes b and d.

Between the lugs E' E', I fit a nut, threaded internally from y to z, to gear into the threads on the bar B. This nut is in two parts, hinged at x, and can be clamped together or opened out, as required. One end of the nut passes through one of the lugs, and carries a ratchet-wheel, D, actuated by a pawl on the piston-rod of the cylinder P. As this wheel is turned, the engine is caused to advance, as before explained.

When it is necessary to return the engine, to commence a fresh working, the nut is opened out to disengage the threaded portion from the bar B, the engine is pushed back the required distance, and the nut closed and clamped. Mitre-gearing, fitted with a handle, may be employed, by turning which handle the engine can be moved back upon the bars B C, to begin a fresh hole, or the engine may be moved back by rotating the bar D, or otherwise.

Sometimes I employ two distributing-cylinders, one of them being arranged to work the valve-cylinder N, and the other to work the pawl-cylinders O and P.

When I employ steam, instead of compressed air, as the motive-agent, I enclose the valve of the cylinder A in a box or casing, and use the ports in the ordinary manner.

What I claim as my invention, and desire to secure by Letters Patent, is—

1. The combination of the following elements or parts, viz, first, an ordinary cylinder, provided with a piston and piston-rod, suitable for supporting a boring-tool; second, a distributing-cylinder, provided with ports and pistons, actuated from the rod of the ordinary cylinder, the combination being substantially as described.

2. The combination of the following elements or parts, viz, first, an ordinary cylinder, provided with a piston and rod suitable for supporting a boring-tool; second, a distributing-cylinder, provided with ports and pistons, actuated from the rod of the ordinary cylinder; third, a cylinder actuating a pawl, the combination being substantially as set forth.

3. The combination of the following elements or parts, viz, first, an ordinary cylinder, provided with a piston and piston-rod suitable for supporting a boring-tool; second, a distributing-cylinder, provided with ports and pistons, actuated from the rod of the ordinary cylinder; third, a cylinder actuating a pawl, the combination being substantially as set forth.

4. The combination of these elements or parts, viz, first, an ordinary cylinder, provided with a piston and rod suitable for supporting a boring-tool; second, a distributing-cylinder, provided with ports and pistons, actuated from the rod of the ordinary cylinder; third, two cylinders, actuating each a pawl, the one to revolve the tool, the other to advance the boring-tool towards its work, the combination being substantially as described.

In witness whereof, I, the said FREDERICK BERNARD DÆRING, have hereunto set my hand, this third day of August, one thousand eight hundred and sixty-seven.

F. B. DÆRING.
